UNITED STATES PATENT OFFICE.

JOHN H. SMIDLEY, OF BALTIMORE, MARYLAND.

VENTILATOR.

1,369,566.

Specification of Letters Patent. Patented Feb. 22, 1921.

Application filed March 31, 1920. Serial No. 370,225.

To all whom it may concern:

Be it known that I, JOHN H. SMIDLEY, a citizen of the United States, residing at Baltimore, State of Maryland, have invented new and useful Improvements in Ventilators, of which the following is a specification.

My invention relates to ventilators and will be described as adapted for use in windows or window openings in houses and other buildings. It is to be understood, however, that the improved ventilator is capable of use in other places where proper and satisfactory ventilation is needed.

The object of my invention is to provide a ventilator which is automatic, positive and noiseless in operation and controlled entirely by air pressure and gravity in the closing and opening movements thereof; also one which cannot get out of order and is practically indestructible in use under ordinary conditions.

A further object of the invention is to provide a ventilator embodying in conjunction with a suitable housing or casing, a closure freely movable with minimum friction and arranged to be moved by air pressure to a closed position and also adapted to be moved to its normally open position by gravity; to eliminate noise and to render the operation of the closure more or less sensitive to air pressure.

The improved ventilator opens and remains open under ordinary light air pressure permitting air to pass by the same and is automatically closed by air pressure when the latter becomes excessive or such as to produce a draft upon persons within the house and in the vicinity of the ventilator when placed in a window or other opening.

A further object in view is to provide in conjunction with a window, or other opening, upper and lower ventilating members to admit air to the interior of the house and permit air to flow to find exit therefrom; one of such ventilating members, (preferably the lower one) being more sensitive than the other to adequately protect persons in the vicinity thereof. In this way a circulation of air is obtained without any discomfort or danger to such persons.

The invention consists in the novel combination and arrangement of instrumentalities herein shown, described and claimed.

In the accompanying drawings:—

Figure 1 is a vertical cross section through

a window frame and opening, showing the use of upper and lower ventilators in proper relation thereto and to the top and bottom window sashes.

Fig. 2 is a vertical cross section through the upper ventilator on an enlarged scale.

Fig. 3 is a fragmentary outside elevation of the same.

Fig. 4 is a fragmentary inside elevation thereof.

Fig. 5 is a fragmentary horizontal section through the same.

Fig. 6 is a vertical cross section through the lower ventilator.

Fig. 7 is a fragmentary outside elevation of the same.

Fig. 8 is a fragmentary inside elevation thereof.

In the preferred installation of the improved ventilator, I employ in conjunction with a window 10 and top and bottom sashes 11 and 12, an upper ventilator or ventilating member 13 and a lower ventilator or ventilating member 14. Such installation permits air to enter a building through the lower part of the window opening and flow outwardly through the top thereof, and as will hereinafter appear, in case of gusts or excessive winds or air pressure both the upper and lower ventilating members will automatically close, preventing dust, smoke, snow, and the like from being blown into the building.

The lower ventilator or ventilating member 14 embodies a housing or box-like casing shown as comprising an outside wall 15, an inclined inside wall 16 and an outwardly sloping or inclined bottom surface 17. The wall 15 is formed with an air inlet 18, and the wall 16 is formed with an air outlet 19 which is surrounded by a seating flange 20 for a freely and bodily movable closure 21.

The closure 21 is shown in the form of a hollow hemisphere and half ball as shown in Fig. 6 and is disposed with its open side toward the inlet 18 and its convex side toward the outlet 19 so that it may seat against the flange 20 and obstruct and close the same to exclude air from the building. The closure 21 is freely suspended in the housing by means of a cord or chain 22 or its equivalent attached to the top of the housing by a hook or eye 23 or the like and attached to the closure 21 at opposite places on the latter as indicated in Figs. 6 and 7. The distance between the inlet 18 and the

outlet 19 is such that under low air pressure the closure 21 hangs suspended between the inlet and outlet and does not obstruct the passage of air through the housing. 5 Under sufficient air pressure, however, the closure 21 is pressed against its seat 20 closing the outlet 19 and stopping the flow of air. As the closure 21 is composed of some soft or resilient material such as fiber, 10 leather or rubber it acts noiselessly and is very sensitive to air currents.

A hood or air-distributing wall 24 is arranged at the inner side of the wall 16 forming an air-distributing chamber 25 which 15 divides the whole incoming current into a great number of smaller currents which are not attended with discomfort and danger to persons nearby. The housing is further shown as equipped with a packing or 20 weather strip 26 for air-excluding contact with the adjacent window sash, as shown in Fig. 1. The strip 26 is clamped between parts of the housing as shown in Fig. 6.

The upper ventilator or ventilating member 13 embodies an outside wall 27 having an air port 28, an inside wall 29 having a port 30, a top wall 31 and an outwardly sloping or inclined bottom surface 32. The port 30 is partially obstructed by a reticulated guard 33 which forms a seat and stop for a closure 34 restrained as to its amplitude and direction of movement by an open-work or meshed wire cage 35 having an obstructed end wall 36 and freely open at the 35 opposite end as shown in Fig. 5. The end 36 is spaced from the port 28 so the closure 34 cannot obstruct the latter but said closure upon being propelled upwardly along the inclined surface 32 may obstruct and close 40 the port 30 to prevent gusts of air, dust and the like from entering the building. When the closure, which is shown in the form of a hollow sphere or ball of soft or resilient material such as rubber, leather or fiber, rolls 45 down the inclined surface 32 by gravity upon reduction of air pressure from the outside, said closure is stopped by the end wall 36 of the cage leaving the ventilator open and free for the passage of air therethrough in either 50 direction. A packing or weather strip 37 attached to the housing of the member 13 contacts with the adjacent window sash, as shown in Fig. 1.

In one ventilator member the closure rolls 55 on an inclined floor or surface under the action of air pressure and gravity while in the

other ventilator member the closure being freely suspended swings under air pressure and gravity. In both cases the closures move bodily or at every point toward and 60 from their closed and open positions and, being of such material as above indicated, such movements are rendered noiseless and accompanied by little or no friction and wear. In each case the housing may be of 65 any necessary length and have any required number of ports, inlets and outlets and a corresponding number of closures and seats as indicated in the drawings. The closure 21, being more sensitive than the closure 34, 70 is generally used at the bottom of a window opening to add to the comfort and safety of persons near the window.

Claims:

1. A ventilator embodying a housing having an air inlet and an air outlet, and a closure for said outlet freely movable as a whole in an inclined path under the action of air pressure and gravity to cover and uncover said outlet, said closure having a working face of spherical formation, and a reticulated seat for said closure adjacent to the air outlet. 75

2. A ventilator embodying a housing having an air inlet and an air outlet, and a resilient closure for said outlet freely movable as a whole in an inclined path nearly horizontal under the action of air pressure and gravity to cover and uncover said outlet. 85

3. A ventilator embodying a housing having an air inlet and an air outlet, and a flexible closure for said outlet freely movable as a whole in an inclined but nearly horizontal path under the action of air pressure and gravity to cover and uncover said outlet. 90

4. In window ventilation, the combination of an upper ventilator and a lower ventilator, each ventilator embodying a housing having an inlet and an outlet, and bodily 100 movable air pressure controlled closures for said inlet and outlet, the closure of the lower ventilator being more sensitive to air pressure than the closure of the upper ventilator.

5. In a ventilator, a housing having an 105 air inlet and an air outlet and also having an inclined floor between said inlet and outlet, and a freely movable unrestrained spherical closure supported by said inclined floor and movable between said inlet and outlet. 110

In testimony whereof I affix my signature.
JOHN H. SMIDLEY.
